COMBINED BILLFOLD AND PICTURE HOLDER OR THE LIKE

William Lipp, New York, N. Y.

Application July 9, 1951, Serial No. 15,793

Term of patent 7 years

(Cl. D87—3)

To all whom it may concern:

Be it known that I, William Lipp, a citizen of the United States of America, residing in New York, county of New York, and State of New York, have invented a new, original, and ornamental Design for a Combined Billfold and Picture Holder or the like, of which the following is a specification, reference being had to the accompanying drawing, forming part thereof.

Fig. 1 is a perspective view of a combined billfold and picture holder or the like, showing my new design.

Fig. 2 is a rear view thereof.

Fig. 3 is a plan view illustrating the combined billfold and picture holder or the like in open position.

Fig. 4 is a fragmentary view of Fig. 3, illustrating the picture holder removed.

I claim:

The ornamental design for a combined billfold and picture holder or the like, substantially as shown.

WILLIAM LIPP.
